(57) **CLAIM**

The ornamental design for a cover for a lawn trimmer, as shown and described.

DESCRIPTION

FIG. 1 is a front perspective view of a cover for a lawn trimmer showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a front perspective view thereof shown in use condition attached to a lawn trimmer.

The broken line showing of environment in FIGS. 6-9 forms no part of the claimed design.
